UNITED STATES PATENT OFFICE.

GEORGE D. HAWORTH, OF CHICAGO, ILLINOIS.

GRAIN-DRILL.

SPECIFICATION forming part of Letters Patent No. 659,227, dated October 9, 1900.

Application filed July 19, 1900. Serial No. 24,130. (No model.)

To all whom it may concern:

Be it known that I, GEORGE D. HAWORTH, of the city of Chicago, State of Illinois, have invented certain new and useful Improvements in Grain-Drills, of which the following is a specification.

This invention relates to means for lifting and yieldingly depressing the runners or furrow-openers of grain-drills and similar implements. It is exemplified in the structure hereinafter described and it is defined in the appended claims.

In the drawings forming part of this specification, Figure 1 is a side elevation of an embodiment of my invention, showing the runners supported at about the level of the ground. Fig. 2 is a similar elevation showing the runners forced yieldingly into the soil. Fig. 3 is a rear elevation of one of the brackets used to connect the draft-bars of the runners with the front cross-bar of the drill-frame.

The bracket 1 has pivot-pins 1^a, on which the draft-bars swing, and depending-fingers 1^b, which hold the bars on the pins while the bars are in operative positions. The fingers are far enough from the pins to permit the bars to be slipped onto the pins narrowwise, and when the bars are in operative positions 30 the upper ends of the bars extend behind the fingers and hold the bars in connection with the bracket. Central lugs 1^c provide means for connecting springs with the bracket.

The draft-bars 2 are pivoted at their upper 35 ends on the pins of the bracket or are otherwise pivotally connected with the drill-frame, and their lower ends embrace and are secured to the front end of the furrow-opening runner or shoe 3. A bent lever 4 is pivotally connected with the draft-bars at 5 and it extends upward and backward toward the seed-tube 10 of the runner. A stop is provided to prevent upward swing of lever 4 on pivot 5 beyond a certain limit, and in this instance such 45 stop consists of a pin 6, inserted through a hole in the lever in position to strike against the draft-bars when the lever has reached the limit of its upward independent swing. The rear end of the lever is preferably forked to 50 straddle the seed-tube, so that the lever may

be held by the tube in line with the runner and side wabble be avoided. The pivot 5 of lever 4 is near the lower ends of the draft-bars. In this instance the lever extends upward and approaches the pivot of the draft-bars before turning rearward, and a spring 55 7 connects with the forward extension of the lever and with the lug 1^c of the bracket 1. A plurality of hitch-holes 8 are preferably made in the lever, so that the connection of 60 the spring with the lever may be shifted and the application of spring-tension to the lever be varied.

The runner 3 is raised or lowered by force applied to the lever 4 in the rear of the fulcrum 65 thereof, and downward pressure on the lever is exerted on the runner to an extent dependent on the strength of spring 7. If the spring were omitted, the lever would swing downward without affecting the furrow-former; 70 but the resistance of the spring to the downward swing of the lever is transmitted to the runner as downward pressure thereon. The lift of the furrow-former is independent of the spring, and the point in the swing of the 75 lever at which upward motion is imparted to the runner depends on the location of the stop 6. In Fig. 1 the stop is shown in contact with the draft-bars and upward stress on the lever is imparted to the runner through 80 the bars.

The means employed to raise and lower lever 4 are independent of this invention; but they preferably comprise a rock-shaft, as 13, a lever 14 to rock the shaft-arms 12, fixed on 85 the rock-shaft, and rods or bars 11 extending from the arms to levers 4.

I claim—

1. The combination with a furrow-former hitched at its forward end to swing vertically, 90 of a lever pivotally connected with the draft-bar of the furrow-former in the rear of the pivot thereof and a spring to impart downward pressure on the lever to the furrow-former, substantially as described. 95

2. The combination with a furrow-former hitched at its forward end to swing vertically, 100 of a lever pivotally connected with the draft-bar of the furrow-former in the rear of the pivot thereof and an extension-spring hitched

to the lever and extended forward therefrom, whereby downward pressure on the lever is yieldingly imparted to the furrow-former.

3. The combination with a furrow-former hitched at its front end to swing vertically, of a bent lever pivoted to the draft-bar of the furrow-former in the rear of the pivot thereof and extended upward and backward, and an extension-spring hitched to the lever at the rearward turn thereof and extended forward therefrom.

4. The combination with a furrow-former hitched at its front end to swing vertically, of a lever pivotally connected with the draft-bar of the furrow-former back of the pivot thereof, a spring to impart downward pressure on the lever to the furrow-former and a

stop to limit upward swing of the lever independent of the furrow-former, substantially as described.

5. The combination with a furrow-former hitched at its forward end to swing vertically, of a supporting-bracket for the furrow-former having pivot-pins for the draft-bars of the furrow-former and also having guard-fingers 25 to hold the bars on the pins, substantially as described.

In testimony whereof I sign my name in the presence of two subscribing witnesses.

GEO. D. HAWORTH.
